Attorney

UNITED STATES PATENT OFFICE.

FREDERICK M. BROWN, OF LOS ANGELES, CALIFORNIA.

CEILING INSULATOR FOR DISCHARGE PIPES OF GAS STOVES AND GAS WATER HEATERS.

Application filed April 9, 1925. Serial No. 21,956.

The invention relates to means for insulating the flues of gas stoves to prevent fire hazards therefrom and has for its object the provision of a device made of refractory material that is capable of being readily mounted in the ceiling and will protect the woodwork thereof from becoming heated by the flue from the gas stove.

The construction and operation and advantages of the invention will be clearly described hereinafter and will be found illustrated in the accompanying drawings in which

Figure 1 is a central vertical sectional view of the improved insulator showing it mounted in the ceiling, and

Figure 2 a bottom plan view.

In the drawings similar reference characters will be used to designate corresponding parts throughout the several views.

The improved insulator consists of a tubular member 1 having a lateral flange 2 on its upper edge and a lateral flange 3 on its lower edge provided with openings 4. The bore 5 of the tubular portion 1 is designed to receive the sheet metal flue pipe A that is usually connected with a gas stove to carry off the carbon monoxide and other products of combustion. The upper end of the tubular member has an enlarged recess 6 to receive a terra cotta pipe or tile B, preferably of the same interior diameter as

the flue pipe A, said pipe B extending outside of the house or other building to the atmosphere.

The insulator is designed to be made of any refractory material such for instance as concrete, fire clay or other suitable fire resisting material and is designed to protect the rafters C of a building as well as the lathing D and plaster or other ceiling E. It is mounted in position as shown in Figure 1 by inserting blocks of suitable thickness indicated at F between the rafters C and the flange 2. When in position the openings 4 provide for ventilation of the compartment in which the gas stove is situated.

What is claimed is:—

A ceiling insulator for discharge pipes of gas stoves, comprising a tubular portion adapted to receive a discharge pipe, a flange on the upper end of said tubular portion to support it in position, a flange on the lower end of said tubular portion and having ventilating openings therein, and the upper end of the tubular portion provided with a recess communicating with the bore thereof and adapted to receive and support a pipe for the purpose stated.

In testimony whereof I affix my signature.

FREDERICK M. BROWN.
